UNITED STATES PATENT OFFICE.

LAURANCE MAYER, OF NEW YORK, N. Y., ASSIGNOR TO JULIUS KAYSER & CO., OF NEW YORK, N. Y., A CORPORATION OF NEW YORK.

LADY'S UNDERGARMENT.

1,106,663.

Specification of Letters Patent. Patented Aug. 11, 1914.

Application filed December 30, 1913. Serial No. 809,486.

To all whom it may concern:

Be it known that I, LAURANCE MAYER, a citizen of the United States, and a resident of the borough of Manhattan, city, county, and State of New York, have invented a new and useful Improvement in Ladies' Undergarments, of which the following is a specification.

The purpose of this invention is to provide close-fitting and comfortable undergarments or drawers for ladies' wear and to this end the garment is made in the general form of a bag closed at the bottom, with leg openings at the opposite vertical edges and having an open top adapted to encircle the waist of the wearer. The open top will be equipped with an elastic closure of suitable construction, or with draw-strings, tapes or similar devices, whereby the garment may be supported from the waist of the wearer and yet easily and quickly lowered or removed whenever desired.

Referring to the drawings, Figure 1 illustrates an elevation of a garment embodying the invention viewed from the front; Fig. 2 illustrates the same garment viewed from the front and showing the position it assumes upon the body of the wearer when in use.

In the drawings, 1 represents the body of the garment. It is made of such fabric as desired and in the general form of a bag having a closed bottom, as at 2, and an open top, as at 3. About the opening 3 suitable elastic material, as at 4, may be inclosed in a hem or otherwise attached, or draw-strings may be employed in a manner well known. The bag-like body part is preferably enlarged somewhat at about the middle of its height, and extending thence to the bottom, as shown at 5, 5. Leg openings 6, one at each side, are provided, which will preferably be finished with some suitable ornamenting material, as lace, ruffles, or the like, as shown at 7, 7.

In applying the garment, the wearer thrusts her legs through the open top 3, passing one leg through one of the lateral leg openings and the other leg through the other leg opening, and as the garment is drawn upwardly and fastened about the waist, or allowed to so fasten itself, if automatic elastic material is provided at the open top, the rotundity of the abdomen in

front and the rearward projection of the seat of the wearer behind, plus the inward movement of the lower parts of the leg openings, cause the central part of the bottom of the bag-like body part to move upwardly, gathering the material at the crotch, as shown in Fig. 2.

A number of advantages are secured by the construction described. The cost is reduced. All buttons or equivalent fasteners are eliminated. The garment automatically adjusts itself to the body formation of the wearer without any drawing or straining, hence comfort is secured to a marked degree and all parts of the pelvic region of the wearer are covered by the continuous bag-like garment, thus securing warmth and generally hygienic conditions. The garment has a clinging fit, admirably adapted for wear with ladies' outer garments now in vogue. It also combines the appearance of a petticoat with the comfort and adaptability of a knickerbocker and fits snugly about the leg above the knee without the use of any elastic or equivalent device, to bind the wearer.

The details of construction may obviously be changed without departing from the essentials of the invention.

I claim:

1. An undergarment comprising a bag-like body part having a permanently closed front and rear portion and a continuous closed bottom, a substantially vertical continuous leg opening at each side near the bottom and an open top provided with means whereby the garment may be supported from the waist of the wearer.

2. An undergarment comprising a bag-like downwardly enlarging body part having a permanently closed front and rear portion and a continuous closed bottom, a substantially vertical continuous leg opening at each side of the body part extending from the bottom thereof upwardly and means whereby the garment may be supported from its upper edge.

In testimony whereof I have signed my name to this specification in the presence of two subscribing witnesses.

LAURANCE MAYER.
